PROCESS FOR POLYMERIZING UNSATURATED HYDROCARBONS

Rudolph C. Osterstrom, Chicago, Ill., assignor to
The Pure Oil Company, Chicago, Ill., a corporation of Ohio

Application November 20, 1930, Serial No. 496,972

9 Claims. (Cl. 196—9)

This invention relates to an improved process of producing gasoline-like hydrocarbons from unsaturated hydrocarbons, and has for its primary object the provision of a process for treating unsaturated hydrocarbons developed by cracking and other similar operations, whereby to render such hydrocarbons efficient for use as motor fuels, to reduce the amount of fixed gas developed by such operations and to treat the gasoline-like distillates to remove therefrom compounds of an objectionable nature when such distillates are intended for use as motor fuels.

In the cracking of high boiling oils in the vapor phase, it is customary to employ relatively high temperatures during the conversion or cracking operation. Such high temperatures result in the formation of very substantial quantities of gas in proportion to the total amount of oil charged to the cracking operation. In a prior application filed by Cary R. Wagner, Serial No. 283,145, filed June 5, 1928, a process is set forth wherein such gas is passed at elevated temperatures and pressures through a heated zone and therein maintained under conditions promoting the polymerization of the gas into compounds possessing higher molecular weights and which fall within the range of gasoline.

In addition, vapor phase cracked distillates contain certain undesirable compounds which, upon standing, produce gums or resinous deposits tending to discolor the distillates and to render them objectionable for use in internal combustion engines as a fuel. In the co-pending application filed by the applicant, Rudolph C. Osterstrom, Serial No. 447,532, filed April 26, 1930, of which this application is a continuation-in-part, a process has been set forth for removing such deposits from vapor phase cracked distillates by passing the latter through a heated reaction zone maintained under superatmospheric pressures and high temperatures whereby to polymerize the objectionable compounds which produce the aforesaid resinous deposits. In accordance with the present invention, a process is provided wherein polymerization reactions on the part of the gas and the motor fuel distillate take place in a single treating system to the end of reducing the equipment costs and to obtain other highly desirable operating economies.

In the accompanying drawing, which forms a part of this specification, the single figure illustrates diagrammatically apparatus used in carrying out the present invention.

Referring more particularly to the drawing, the numeral 1 designates a pipe line through which

is passed a vapor phase cracked petroleum distillate in an untreated condition and containing a large percentage of certain highly reactive unsaturated hydrocarbons which require removal before the distillate is rendered suitable for commercial distribution and use. The pipe line 1 enters a working tank 2 in which is also contained hydrocarbon gas of the type produced by, for example, vapor phase cracking operations. This gas may enter the tank 2 either through the pipe line 1 or by any other desired method of introduction. As is well known, refinery gas of this character, also, contains a large percentage of unsaturated hydrocarbons.

Leading from the bottom of the tank 2 is a pipe line 3 by which the gasoline distillate is conducted to the suction side of pump 4. The discharge side of the pump 4 is connected with a pipe line 5 which leads to a heating coil 6 disposed in a suitable furnace 7. The furnace is provided with burner means, indicated at 8, by which adequate heat is developed within the furnace to raise the temperature of the hydrocarbons passing through the coil to a polymerization temperature which may vary between substantially 300° F. to 750° F. The pump 4 operates preferably to maintain the distillate during its flow through the coil 6 under superatmospheric pressures varying between 500 to 1200 pounds per square inch in order that the gasoline distillate, undergoing treatment, will be maintained substantially in the liquid phase, although vaporization of the distillate under treatment may be provided for in the coil 6 under certain circumstances by the use of lower pressures.

The gas withdrawn from the top of the tank 2 passes by way of a pipe line 9 to a compressor 10 and from the compressor 10 to an accumulator 11. In this accumulator the gas is maintained under a pressure of approximately 175 pounds per square inch. Within this accumulator there takes place a separation of low boiling liquid oils from the gases, and these oils are withdrawn from the bottom of the accumulator, together with gases dissolved therein, by way of a valve controlled pipe line 12, which leads to a pump 13 and from the discharge side of this pump to the pipe line 5.

Leaving the top of the accumulator 11 is a valve pipe line 14 which extends to a compressor 15 wherein the pressure on the gas is increased to approximate the pressure which obtains in the line 5, and a pipe line 16 connects the discharge side of the compressor 15 with the pipe line 5 immediately ahead of the coil 6.

By this method of operation it will be observed that both the gasoline distillate and the gas will pass as a mixed stream through the polymerization zone formed by the coil 6. The coil is preferably formed from ordinary mild steel sections of pipe of desired length and may or may not contain a catalyst, such as aluminum chloride, nickel chloride or other metallic halids. In the preferred form of my invention I have found it unnecessary to employ a catalyst in the coil 6 although, of course, such a catalyst as those of the type described may be used if desired. The unsaturated gases introduced into the coil preferably contain propylene, butylene and, in certain instances, ethylene. Gases such as propylene and butylene, show a marked tendency to polymerize under the conditions of elevated temperature and pressure present in the coil 6. The polymerization of these gases results in the formation of additive compounds of higher molecular weights, which, upon subsequent cooling or condensation, possess the boiling range of motor fuel.

While the gases are being polymerized in the single coil 6, likewise polymerization of certain undesired compounds present in the distillate removed from the bottom of tank 2 takes place. The vapor phase cracked distillate possesses, when untreated, certain highly reactive unsaturated compounds which, in time, produce particularly upon exposure to air undesired gums and color producing bodies. By accelerating the rate of polymerization of these undesirable compounds in vapor phase cracked distillate, the same may be separated from the distillate at the time the motor fuel is being manufactured so that the latter will remain stable, in so far as gum content and color are concerned. I have found that by passing a vapor phase cracked distillate through a polymerizing zone such as the coil 6 under conditions of elevated temperatures and pressure, that the polymerization of these gum-formed and color-producing bodies can be secured, and therefore I make use of the coil 6 for this purpose, whereby the single coil serves the double function of polymerizing both the gas and the undesired compound in the distillate.

The treated hydrocarbons are discharged from the coil 6 by way of a pipe line 17, and enter a vessel 18 in which is contained a bed of fuller's earth or other equivalent materials. Preferably, pressure is maintained on the distillate to maintain the latter in the liquid phase while passing through the fuller's earth bed in vessel 18. The fuller's earth may be said to act either as a catalyst or adsorbent in effecting further polymerization of the selected hydrocarbons. The treated oils are passed from the vessel 18 by way of a pipe line 20 to a stabilizing column 21 and the line 20 may be provided with a pressure reducing valve 22 by which separation of the heavy polymerized compounds from the lighter and desired products is permitted to take place in said column. The heavy polymerized compounds collect in the bottom of column 21 and may be removed by means of the valve controlled outlet 23, whereas the desired lighter hydrocarbons, by reason of the temperatures which prevail in column 21, assume a vaporous form, especially in view of the reduced pressures, and pass overhead from the column through an outlet line 24 together with the remaining fixed gas. The line 24 extends to a condenser 25 and thence to a gas separator 26 by which the fixed gas may be removed from the system and put to any suitable use. The treated distillate is removed from the bottom of the sepa-

rator 26 and passed to a stabilizer 28 to insure the removal of all fixed gas from the distillate. The fixed gas finds outlet through the lines 29-29 connected with the separator 26 and the stabilizer 28, and the stabilized gasoline-like hydrocarbons are removed by way of the line 30, connected with the bottom of the stabilizer and passed to a storage tank 31 as a finished commercial motor fuel.

In view of the foregoing, it will be seen that the present invention provides a method for treating low boiling cracked oils, obtained especially from vapor phase cracking plants, to remove from such oils undesired gum-forming and color-forming compounds. At the same time refinery gas, which is developed in relatively large quantities by the operation of high temperature or vapor phase cracking units, is subjected to a polymerizing operation whereby a large proportion of the gas is converted into higher boiling products having the characteristics of an anti-knock gasoline. Both of these operations, which I now consider to be the result of polymerization, take place in a single treating system which includes a heating unit, instead of taking place in separate systems as was heretofore done. This improved combined treating system results in decreasing equipment and operating costs and provides generally for increasing the yields of the desired motor fuel end product of vapor phase cracking systems.

While I do not desire to be limited by the following explanation of reactions which take place in my process, yet it is my opinion that one explanation for the favorable results obtained is as follows: In the presence of normally liquid hydrocarbons, such as the low boiling distillate undergoing gum removal treatment, I am able to maintain ethylene, propylene and butylene in solution in the liquid state whereas they normally would exist in a gaseous condition. As a result of this change of state, the molecules of these unsaturated gases are brought closer together and caused to collide with each other more frequently and thereby increasing the tendency thereof to polymerize.

While I have described the invention as being especially applicable for use in connection with vapor phase cracking systems, nevertheless I do not limit myself to such systems or operations but reserve the right to employ the invention in any capacity where it may be used to advantage.

What is claimed is:

1. The method of polymerizing unsaturated hydrocarbons, which consists in passing a mixture composed of unsaturated hydrocarbon gases and a cracked low boiling oil containing unsaturated compounds through a heated reaction zone, heating the mixture during its passage through said zone to a temperature varying between 300° F. to 700° F., while said mixture is maintained under superatmospheric pressure, then passing said mixture, following its removal from said heated reaction zone through a stationary body of fuller's earth, and then separating the undesired polymerized compounds from the desired low boiling oils and remaining fixed gas.

2. The method of polymerizing unsaturated hydrocarbons, which consists in passing a stream of such hydrocarbons consisting of a mixture of cracked low boiling oils containing unsaturated compounds and unsaturated hydrocarbon gases through an externally heated reaction zone, heat-

ing the mixture during its passage through said reaction zone while under superatmospheric pressure to a polymerizing temperature wherein no substantial cracking of the hydrocarbons comprising the mixture takes place, then passing the mixture from the reaction zone through a bed of fuller's earth and finally reducing the pressure on the mixture to permit of the separation of high boiling polymerized compounds from the 10 treated lighter compounds.

3. The method of treating unsaturated hydrocarbons, which consists in continuously passing a mixture composed of a cracked low boiling oil containing undesirable unsaturated compounds 15 and an unsaturated hydrocarbon gas through a heated reaction zone, maintaining the mixture during its passage through said zone under superatmospheric pressure, heating the mixture during its passage through said zone to a temperature 20 sufficiently high to effect therein polymerization of said undesirable compounds and unsaturated constituents of said gas while avoiding any substantial cracking of the hydrocarbons comprising the mixture, discharging the mixture 25 from the reaction zone under reduced pressures into an expansion chamber, and removing from one portion of said chamber high boiling polymerized compounds and from another portion of said chamber the desired treated compounds.

4. In the treatment of unsaturated hydrocarbons obtained from vapor phase cracking operations, the steps which comprise continuously passing a mixture composed of cracked low boiling oils containing unsaturated hydrocarbons 30 and an unsaturated hydrocarbon gas through an elongated externally heated reaction zone, maintaining the mixture during its passage through said zone under superatmospheric pressure, heating the mixture during its passage 35 through said zone to a temperature varying between 300° F. to 750° F., while avoiding any substantial cracking of the hydrocarbons comprising the mixture, reducing the pressure on the mixture following its release from said reaction zone 40 and separating from the mixture undesirable polymerized compounds.

5. In the treatment of unsaturated hydrocarbons obtained from vapor phase cracking operations, which consists in continuously passing a mixture 50 composed of unsaturated hydrocarbon gases and cracked low boiling oils containing unsaturated compounds through a tube still, heating the mixture during its passage through said still to a temperature varying between 300° F. to 750° F., maintaining the mixture during its passage through 55 said still under superatmospheric pressures sufficiently high to maintain the low boiling oils in the liquid phase, removing the mixture from said still and, without reducing the pressure thereon, passing said mixture through a bed of fuller's earth, and then passing the mixture under 60 reduced pressures into an expansion chamber, whereby to separate undesirable polymerized compounds from the treated mixture.

6. The method of polymerizing unsaturated hydrocarbons obtained from vapor phase cracking operations, which consists in passing a mixture composed of cracked low boiling oils containing unsaturated compounds and unsaturated 65 hydrocarbon gases through a tube still, heating the mixture during its passage through said still to reaction producing temperatures varying between 300° F. to 750° F., maintaining the mixture while in said still under superatmospheric 70 pressures, then bringing the mixture following its

discharge from said still into contact with a catalyst capable of promoting polymerizing reactions, and finally passing the mixture into a separating zone under reduced pressure to effect the removal of the undesired polymerized compounds therefrom.

7. The method of treating unsaturated hydrocarbons, which consists in producing a mixture of a low boiling vapor phase cracked distillate containing undesired unsaturated hydrocarbons of a gum-forming and color-imparting character and an unsaturated hydrocarbon gas obtained from a vapor phase cracking operation, passing said mixture of liquid and gas through an elongated heating zone of restricted cross sectional 15 area while said mixture is maintained under a pressure varying between 500 and 1200 pounds per square inch and wherein the mixture is heated to a temperature varying between 300° F. and 750° F., maintaining the mixture in said 20 heating zone for a sufficient period of time to secure desired polymerizing reactions, then without substantial reduction in pressure removing the heated mixture from the heating zone and passing same through a treating zone, bringing 25 said mixture during its passage through said treating zone into contact with a finely divided solid adsorbent during uninterrupted passage of the mixture through said treating zone, reducing the pressure on the mixture 30 following its discharge from the treating zone and fractionating said mixture in a fractionating zone, removing from one portion of said fractionating zone liquid hydrocarbons having a boiling 35 range higher than the cracked distillate originally charged to the heating zone, removing from another portion of said fractionating zone as a vaporous overhead product vapors composed of desired low boiling oils substantially free from objectionable gum-forming and color-imparting 40 bodies and fixed gas, condensing the combined vaporous and gaseous fractions, and separating the condensate from the fixed gas.

8. The method of treating low boiling hydrocarbons produced by vapor phase cracking of 45 high boiling oils into low boiling oils, which comprises: producing a flow stream composed of a mixture of a low-boiling vapor phase cracked distillate containing undesired unsaturated hydrocarbons which tend to produce gums and discoloration in the distillate and an unsaturated hydrocarbon gas capable of being transformed in part into liquid hydrocarbons, passing said flow stream through a heating zone wherein said flow stream attains a temperature varying between 500° F. and 750° F. while held under a pressure varying between 500 to 1200 pounds per square inch, maintaining said flow stream in said heating zone for a sufficient period of time to effect polymerization of the undesired compounds 55 present in the cracked distillate and certain of the gaseous hydrocarbons into liquid hydrocarbons, then passing said flow stream under reduced pressure into a fractionating zone, removing from one portion of said fractionating zone 60 the undesired compounds contained in said distillate in the form of a reflux condensate having an average boiling range higher than that of said distillate forming the flow stream, separately removing from another portion of said zone a 65 vaporous overhead fraction composed of hydrocarbons of gasoline boiling range and fixed gas, condensing the last-named fraction and separating the condensate from the fixed gas.

9. The method of treating unsaturated hydro-

carbons obtained from vapor-phase cracking operations, which comprises continuously passing a mixture composed of normally gaseous unsaturated hydrocarbons and cracked low-boiling oils 5 containing unsaturated compounds undesired in the final product through a tube still under superatmospheric pressure, heating the mixture during its passage through said still to a reaction temperature of from 300° to 750° F. to effect a 10 polymerization of normally gaseous hydrocarbons to normally liquid hydrocarbons lying within a motor-fuel boiling-point range and a polymeriza-

tion of said undesired unsaturated compounds to polymers lying above the motor-fuel boiling-point range, while avoiding any substantial cracking of hydrocarbons comprising the mixture, subjecting the mixture while maintained at such temperature to contact with a solid adsorbent catalyst, and then passing the mixture under reduced pressure into an expansion chamber to effect a separation of relatively high-boiling undesired polymerized compounds from the treated 10 mixture.

RUDOLPH C. OSTERSTROM.
